SHAVING CLIPPER

Frank J. Winder, Toledo, Ohio

Application May 4, 1938, Serial No. 206,001

6 Claims. (Cl. 185—37)

This invention relates to shaving clippers and its principal object is to provide a shaving clipper having manually operable means for imparting rapid reciprocating movement to a shaving cutter.

Another important object of the invention is to provide a shaving clipper having manually operable means for storing energy and means for transmitting the energy so stored to a reciprocating cutter.

Another object of the invention is the provision of a shaving clipper having means for converting force intermittently applied to a handle into force continuously acting upon mechanism to impart relatively rapid reciprocating movement to a cutter.

And still another object is to provide an effective manually operable shaving clipper of such form and compactness that it may be carried in a vest pocket or small purse or toilet kit.

Other objects and advantages will be apparent from the following description, in which reference is had to the accompanying drawings illustrating a preferred embodiment of my invention and wherein similar reference numerals designate similar parts throughout the several views.

In the drawings:

Figure I is a view in perspective of one form of shaving clipper embodying my invention;

Figure II is a plan view of the same form of shaving clipper, the upper part of the casing being removed and the shaving head and cutter being shown in section;

Figure III is an elevational view showing the mechanism illustrated in Figure II, the casing, shaving head and cutter and some of the gearing being shown in section;

Figure IV is a plan view of another form of the shaving clipper of my invention, the upper half of the casing being removed and parts being shown in section;

Figure V is an elevational view of the mechanism illustrated in Figure IV, the casing, shaving head and cutter and certain cranks and links being shown in section;

Figure VI is a plan view similar to Figure IV but showing another modification of the operating mechanism;

Figure VII is an elevational view, partly in section, of the mechanism illustrated in Figure VI;

Figures VIII and IX are views similar respectively to Figures VI and VII but showing a further modification of the operating mechanism;

Figure X is an enlarged fragmentary sectional bottom plan view taken along the line X—X of Figure IX;

Figure XI is a plan view, with parts of the upper casing member broken away and with the shaving head and cutter shown in section, illustrating still another form of the operating mechanism of my invention; and

Figure XII is an elevational view of the form of mechanism illustrated in Figure XI, the casing, shaving head, cutter and one of the gear elements being shown in section.

Referring to the drawings in detail and particularly to Figures I, II and III thereof, the operating mechanism of my device is mounted within a casing consisting of a lower member 1 and a similar upper member 2. The casing may be made of stamped or die-cast metal or of a suitable molded plastic, and is small and flat so that it may be conveniently used and carried.

Rigidly interlocked to the forward end of the casing members is a shaving head 3 which may be of any preferred form but which I have illustrated as terminating in a pair of slotted plates 4 and 5 whose outer surfaces lies in planes that intersect at an angle, the edges of the slotted plates being slightly separated. Either the plate 4 or the plate 5 may be laid against and moved over the skin to be shaved; hence, the shaving clipper can be used either side out and manipulated by either the right or the left hand of the user. The apex of the angle at the intersection of the slotted plates lies at the end of the shaving clipper and may be moved up to and under the bows of spectacles, thus enabling persons who prefer to wear glasses while shaving to shave the areas adjacent the bows without displacing them. The arrangement of the plates with the apex of their intersection at the end of the shaving clipper also facilitates shaving adjacent the nose and ears.

The space encompassed by the shaving head with its terminal plates is tubular and diamond shaped in cross section, and mounted for sliding movement therein is a tubular cutter 6 the exterior shape of which conforms to the shape of the space within the head 3. The integral forward blades 7 and 8 of the cutter are slotted to cooperate with the slotted plates 4 and 5, the edges of the teeth formed by the slots in the blades and plates acting in the well known manner, when the blades are reciprocated, to clip hairs which extend into the slots.

Rockably mounted on the trunnions 9 and 10 having bearings in the casing members 1 and 2 is a lever 11, the forward end of which is received in a socket 12 formed in the rear side of the cutter 6, there being a light spring 13 interposed between the end of the lever 11 and the cutter 6 to hold the slotted blades 7 and 8 with uniform pressure against the slotted plates 4 and 5.

The rear end of the lever 11 is forked and receives an eccentric 14 which is fixed upon a shaft 15 journaled in bearings in the casing members 1 and 2. Also fixed upon the shaft 15 are a flywheel 16 and a pinion 17, the pinion teeth meshing with the teeth of a gear wheel 18 that is rotatably mounted upon a stud shaft 19 fixed to the casing member 1.

Integral with the hub of the gear wheel 18 is a pinion 20 the teeth of which mesh with the teeth of an internal oval rack 21. An oblong boss 22 depending from a plate 23 fixed to the rack engages the inner end of the stud shaft 19 and serves to keep the pinion 20 and rack 21 in proper relationship. Extending from the rack 21 outwardly through a slot formed between the casing members 1 and 2 is a link 24 the outer end of which is pivoted to a handle 25. The handle 25 is fulcrumed on one of the screws 26 which secure the casing members together, and is yieldably forced outwardly by a spring 27 but may be manually pressed inwardly into the slot between the casing members. When the handle has been pressed into the slot it may be held therein by a hook 28 which may be engaged with and disengaged from the handle by means of a knurled sector 29 accessible at the end of the casing. When the handle is retained by the hook, the shaving clipper has the appearance illustrated in Figure I.

When the shaving clipper is to be used the handle is unhooked by turning the sector 29 and the spring 27 swings the handle outwardly. With either of the shaving plates 4 or 5 laid against the skin to be shaved, the user presses the handle 25 inwardly, thus imparting rotative movement to the pinion 20 and the gear 18 which acts through the pinion 17 to spin the flywheel 16. As the handle 25 reaches the limit of its inward swing the end of the oval rack 21 rides around the pinion, and when the spring 27 swings the handle outwardly, rotative movement, in the same direction, continues to be imparted to the pinion 20, the gear 18 and the flywheel 16. The energy stored in the flywheel acts through the gearing to cause the handle to swing out and in with a smooth, rhythmic motion.

By repeatedly pressing the handle at each inward swing, thus imparting movement directly to the pinion 20 and at the same time flexing the spring 27 so that it will react during the outward swing to continue imparting movement to the pinion in the same direction, the user keeps the flywheel and the eccentric 14 turning continuously at high speed. The eccentric rocks the lever 11 and thus reciprocates the shaving cutter 6. The high frequency reciprocation of the shaving cutter which results from the relatively low frequency swinging movement of the handle is sustained and steadied by the inertia of the flywheel, and the cutter 6 thus is caused to operate smoothly and effectively.

The form of my device illustrated in Figures IV and V differs from that above described in that a link and crank mechanism is substituted

for the oval internal rack and pinion mechanism of Figures II and III and that two handles instead of one are connected to the gearing. The casing members 1a and 2a, the shaving head 3a, the shaving cutter 6a, the lever 11a, the eccentric 14a and the pinion 17a are similar to the corresponding parts of the form of my device already described with reference to Figures I, II and III. The gear wheel 18a is made heavy so that it may serve also as a flywheel, and is provided with a pair of cranks 23a which are connected by means of links 24a to handles 25a, the handles being yieldably forced outwardly by springs 27a. For carrying compactness, the handles may be pressed into slots between the casing members and held in place by the hook 28a. Since the handles are so connected that they move outwardly and inwardly together, the hook 28a need be engaged with only one handle.

In operation the form of shaving clipper shown in Figures IV and V functions in a manner similar to the form shown in Figures I, II and III, except that the user presses the two handles inwardly instead of pressing only one.

When the operator presses the handles 25a he not only turns the gear wheel 18a, but, at the same time, he flexes the springs 27a so that they will react when the momentum of the gear wheel 18a has carried the links 24a beyond "center," to force the handles outwardly, thus continuing to urge the gear wheel 18a to turn in the same direction.

The modification depicted in Figures VI and VII differs from that of Figures IV and V in that the pinion shaft 15b carries a flywheel 16b and in that the gear wheel 18b is turned by one link 24b and one handle 25b. Since the shaving clipper can be used with either side out, the forms with only one handle may be reversed for convenient operation either in the right hand or the left hand of the user.

The mechanism illustrated in Figs. VI and VII functions to urge the gear wheel 18b and the flywheel 16b to turn, without change of direction, during both the inward and the outward swing of the handle 25b. During the inward swing the force exerted upon the handle by the operator's hand pushes upon the link 24b to turn the gear wheel 18b, and during the outward swing the spring at the handle pivot reacts to cause the handle to pull upon the link 24b and thus continue the turning movement of the gear wheel 18b.

In the form shown in Figures VIII, IX and X the gear wheel 18c is integral with a drum 30c, to the inside wall of which is attached the outer end of a spiral spring 31c, the inner end of the spiral spring being attached to a rotatable shaft 32c. Fixed upon the shaft 32c is a ratchet wheel 33c which is engaged by a spring pressed pawl 34c that is pivoted upon the casing member 1c and acts to prevent the ratchet wheel 33c and shaft 32c from being turned backwardly by the spiral spring. The ratchet wheel 33c is engaged also by a spring pressed pawl 35c pivoted on a flange 36c which is fixed to a pinion 37c mounted for free rotation on a bushing surrounding the shaft 32c. The teeth of the pinion 37c mesh with the teeth of a rack formed upon a link 24c which is pivoted at its outer end to a handle 25c. The handle 25c is swingably mounted at its forward end upon one of the screws which hold the casing members together, and is yieldably urged outwardly by a spring 27c. The teeth of the gear

wheel 18c mesh with the teeth of a pinion 17c upon the shaft of which a flywheel 16c is fixed, the structure and function of the flywheel 16c being similar to the structure and function of the flywheels in the previously described modifications.

When the user presses the handle 25c inwardly it acts through the link 24c, the rack, the pinion, pawl 35c and ratchet wheel 33c to turn the shaft 32c and wind up the spiral spring. When the pressure is relieved the spring 21c swings the handle outwardly but the pawl 34c prevents the spiral spring from unwinding from its inner end by turning the shaft 32c. By alternately pressing and releasing the handle 25c, the user keeps the spiral spring partially wound even while it is unwinding at its outer end in turning the gear 18c and pinion 17c. The spiral spring thus spins the flywheel and imparts a steady, rapid reciprocating movement to the shaving cutter as long as the spring remains partially wound.

In the form of my invention embodied in the shaving clipper illustrated in Figures XI and XII, the handle 25d constitutes a winding key which is fixed upon a shaft 32d. Also fixed to the shaft 32d is a ratchet wheel 33d engaged by a pawl 34d to prevent the shaft 32d from being turned backwardly by the action of a spiral spring 31d, the inner end of which is attached to the shaft. The outer end of the spiral spring 31d is attached to the inner wall of a drum 30d which is fixed upon a gear wheel 18d.

The teeth of the gear wheel 18d mesh with the teeth of the pinion 17d fixed upon a shaft 15d to which is fixed also a flywheel 16d. The spinning movement of the shaft 15d resulting from the action of the spiral spring 31d is transmitted, through a short gear train to an eccentric 14d and a rocking lever 11d, to the reciprocating shaving cutter.

In order to prevent the mechanism from operating before the shaving head has been applied to the skin, a brake 40d, carried by one arm of a bell crank lever 41d, is held in frictional engagement with the flywheel 16d by means of a retractile spring 42d. The other arm of the bell crank lever carries a button 43d which is located outside the casing and is supported by the bell crank lever through an arcuate slot in the casing member. The retractile spring is so anchored to the casing and connected to the bell crank lever that when the button is at one end of the slot the brake is held in contact with the flywheel and when the button is pushed quite to the other end of the arcuate slot the brake is held by the spring out of contact with the flywheel. In using this form of the shaving clipper of my invention, the button is slipped to the left end of the slot to set the brake and the key is turned to wind up the spiral spring. The shaving head then is applied to the skin to be shaved and the brake released. The spring of course is rewound whenever the mechanism runs down.

It will be apparent from the foregoing description that I have provided a simple and compact shaving clipper which may be carried in the user's vest pocket or in a small purse or toilet kit and which may be used during railway, highway or air travel, and under almost all circumstances, whether or not water, light or electric current is available.

The embodiments of my invention herein shown and described are to be regarded as illustrative only, and it is to be understood that the 75

invention is susceptible to variation, modification and change within the spirit and scope of the subjoined claims.

Having described my invention, I claim:

1. In a shaving clipper, in combination, a casing, rotary motion multiplying gearing mounted within said casing, a handle movably mounted on said casing and adapted to be manually pressed inwardly, means connecting said handle to said gearing and driven by oscillation of said handle for converting both inward and outward pressure on said handle into torque for driving said gearing in the same direction, whereby said gearing is driven both by inward and by outward movement of said handle during oscillation thereof, spring means which is flexed and placed under elastic stress when said handle is pressed inwardly, said spring means reacting, when the manual pressure on the handle is relieved, to move said handle outwardly and to continue rotation of said gearing in the direction of rotation caused by inward movement of said handle, a flywheel turned by and sustaining the continuous rotary movement of said gearing, and a lever connected to said motion multiplying gearing and receiving therefrom a plurality of rocking movements about its fulcrum in each direction during each inward and outward movement of said handle.
2. In a shaving clipper, in combination, motion multiplying gearing, a handle adapted to be manually pressed inwardly, means connecting said handle to said gearing and driven by oscillation of said handle for converting both inward and outward pressure on said handle into torque for driving said gearing in the same direction, whereby said gearing is driven both by inward and by outward movement of said handle during oscillation thereof, spring means which is flexed and placed under elastic stress by manual pressure exerted to move said handle inwardly, said spring means reacting, when the manual pressure on the handle is relieved, to move said handle outwardly and to continue rotation of said gearing in the direction of rotation caused by inward movement of said handle, a flywheel turned by and sustaining such continuous rotation of said gearing, and a member receiving a plurality of to and fro movements from said motion multiplying gearing during each inward and outward movement of said handle.
3. In a shaving clipper, in combination, a casing, rotary motion multiplying gearing mounted within said casing, a handle pivoted to said casing and adapted to be swung inwardly by manual pressure, means connecting said handle to said gearing and driven by oscillation of said handle for converting both inward and outward pressure on said handle into torque for driving said gearing in the same direction, whereby said gearing is driven both by inward and by outward movement of said handle during oscillation thereof, spring means connected to said handle to be flexed and placed under elastic stress by inward movement of said handle, said spring means reacting to force said handle outwardly after the completion of its inward movement and thereby continue the rotation of said gearing in the same direction, a flywheel turned by and sustaining the continuous rotation of said gearing, and a member receiving a plurality of to and fro movements from said motion multiplying gearing during each inward and outward movement of said handle.
4. In a shaving clipper, in combination, a

frame in the form of a casing adapted to be carried in a vest pocket, and operating mechanism comprising rotary motion multiplying gearing mounted within said casing and a handle mounted on said casing and adapted to be pressed inwardly, and means connecting said handle to said gearing and driven by oscillation of said handle for converting both inward and outward pressure on said handle into torque for driving said gearing in the same direction, whereby said gearing is driven both by inward and by outward movement of said handle during oscillation thereof, and energy storing means connected to said operating mechanism to store energy when said handle is pressed inwardly, the energy stored in said energy storing means acting upon completion of the inward movement of said handle to continue rotation of said gearing in the same direction and to move said handle outwardly.

5. In a shaving clipper, in combination, a frame in the form of a casing adapted to be carried in a vest pocket, and operating mechanism comprising rotary motion multiplying gearing mounted within said casing and a handle mounted on said casing and adapted to be pressed inwardly, and means connecting said handle to said gearing and driven by oscillation of said handle for converting both inward and outward pressure on said handle into torque for driving said gearing in the same direction, whereby said gearing is driven both by inward and by outward

movement of said handle during oscillation thereof, spring means connected to said operating mechanism to be flexed and placed under elastic stress when said handle is moved inwardly, said spring means acting upon completion of the inward movement of said handle to continue the rotation of said gearing in the same direction and to move said handle outwardly, and a flywheel connected to said gearing to be turned thereby and to sustain the continuous rotary movement thereof.

6. In a shaving clipper, in combination, a frame in the form of a casing, and operating mechanism comprising rotary motion multiplying gearing mounted within said casing and a handle mounted on said casing and adapted to be pressed inwardly, and means connecting said handle to said gearing and driven by oscillation of said handle for converting both inward and outward pressure on said handle into torque for driving said gearing in the same direction, whereby said gearing is driven both by inward and by outward movement of said handle during oscillation thereof, and energy storing means connected to said operating mechanism to store energy when said handle is pressed inwardly and upon completion of the inward movement of said handle to impart energy to said operating mechanism and thereby continue the rotation of said gearing in the same direction and to move said handle outwardly.

FRANK J. WINDER.
